INVENTOR.

John A. Bussert.

UNITED STATES PATENT OFFICE.

JOHN A. BUSSERT, OF MACOMB, ILLINOIS, ASSIGNOR OF PART OF HIS
RIGHT TO JAMES S. MCCLINTOCK, OF SAME PLACE.

IMPROVEMENT IN TONGUE-SUPPORTS.

Specification forming part of Letters Patent No. **173,894**, dated February 22, 1876; application filed
August 16, 1875.

To all whom it may concern:

Be it known that I, JOHN A. BUSSERT, of Macomb, in the county of McDonough and State of Illinois, have invented a new and useful Improvement in Tongue-Supporters; and I do hereby declare that the following is a full, clear, and exact description thereof, which will enable others skilled in the art to make and use the same, reference being had to the accompanying drawing, making a part of this specification.

The object of this invention is to support the tongue of any kind of wagon or carriage, and keep the weight off of the animals' necks, and to allow the necessary vibration of the tongue when running over extremely uneven roads; and its novelty consists in the combination of a plate attached to the front axle-tree, and a slotted bearing attached to the under side of the tongue, with a curved rod provided with a spiral spring and nut, as hereinafter fully set forth.

In the drawing, my invention is shown in perspective, showing the under side of the tongue, in which A represents the tongue, B the axle-tree, to which the hounds o o are attached, between which the tongue A is placed in the usual manner, to which, on the under side, is attached by suitable bearings, i and e, the rod n, which is provided with a spiral spring, s, and nut, d. t represents a plate, which is attached to the axle-tree B. The spiral spring

s is placed over the rod n, one end resting against the bearing e, the other back against the nut d. The rear end of the rod n is slightly curved, and extends back against the plate t. The front end extends through the bearing e for the purpose of allowing the spring to be lengthened. The nut d is for the purpose of tightening up the spring s.

The operation is as follows: The spring s pressing against the bearing e presses the rod n back against the plate t sufficiently to raise the point of the tongue and keep it up in about the usual position, thereby keeping the weight off of the animals' necks. By means of the slots in the bearing i the tongue is allowed to vibrate sufficiently to allow the wheels to run over uneven roads. In extremely uneven roads the rear end of the rod n can slide up or down, as the case may be, on the plate t, which will give extra vibration to the tongue.

Having thus fully described my invention, what I claim as new, and desire to secure by Letters Patent, is—

The combination of the plate t and slotted bearing i with the curved rod n, provided with the spiral spring s and nut d, as described, and for the purpose specified.

JOHN A. BUSSERT.
